UNITED STATES PATENT OFFICE.

EDWIN S. VOTEY, OF NEW YORK, N. Y., ASSIGNOR TO AEOLIAN COMPANY, OF NEW YORK, N. Y., A CORPORATION OF CONNECTICUT.

MUSIC-ROLL-CO尤PLING DEVICE.

No. 832,641.

Specification of Letters Patent.

Patented Oct. 9, 1906.

Application filed September 20, 1905. Serial No. 279,285.

To all whom it may concern:

Be it known that I, EDWIN S. VOTEY, a citizen of the United States, and a resident of the borough of Manhattan, city, county, and State of New York, have invented certain new and useful Improvements in Music-Roll-Coupling Devices, of which the following is a specification.

My invention relates particularly to mechanical musical instruments or mechanical players for musical instruments in which a perforated music-sheet is unwound from and rewound on a roll. Its object is to provide couplings movably mounted on the shafts to accommodate rolls of different lengths or rolls having different engaging members, which may thus be used interchangeably on the same instrument.

Under the present invention one or more of the couplings without being detached from the ends of the shafts when not in use may be adjusted or moved to a non-operative position out of the way of another.

In the particular embodiment of my invention shown in the drawings, Figure 1, partly in front elevation, partly in vertical section, shows my device as engageable with a hollow-ended roll, the coupling and the roll being slightly separated for clearness of illustration. Fig. 2 is an end view of the coupling—in other words, a view on the plane 2 2, Fig. 1. Fig. 3 is a front elevation of the coupling as about to be engaged with a roll provided with the ordinary non-circular pin. Fig. 4 is a like view of the device with the movable member of the coupling in its non-operative position. Fig. 5 is a transverse section on the plane 5 5, Fig. 4, the scale being enlarged. Fig. 6 is a front elevation of a modified form of my device. Fig. 7 is an end elevation of the device shown in Fig. 6. Fig. 8 is a front elevation of the same device with the movable parts of the coupling turned to their non-operative position.

Referring to Figs. 1 to 5 of the drawings, 1 designates a shaft which in practice is mounted on a musical instrument or player for the support of a music-roll. The particular shaft shown is the one located at the right end of the roll and is provided with means for rotating the roll to rewind the music-sheet thereon after playing. As the mounting of the shafts and the means for rotating the driving-shaft are well known, I have not

encumbered the drawings with them. At 55 the end of the shaft 1, as shown, is a coupling member 11, having a bore 12, the wall of which is slotted at 13. Projecting laterally from the member 11 is a lug 14, shown as bifurcate and forming a hinge member for co-operating with a hinge-lug 21 on a coupling 2. As a means of holding the coupling member 2 in either its operative or its non-operative position I introduce frictional resistance to the adjusting movement of the member preferably by making the pintle 15 of the hinge in the form of a screw engaging into one side of the lug 14 and carrying a thrust-spring 16, which forces a washer 17 against the side of the hinge member 21. (See Fig. 5.) The coupling member 2 has an approximately cylindric portion 22, having a bore 23 and slots 24 similar to the bore 12 and slots 13 in the coupling member 11. It is also formed with a laterally-extending flange 25, having a forwardly-extending portion 26, bounded by arc-shaped recesses 27, in one of which is a pin 28. Arc-shaped rims 29 form the periphery of the flanged portions 25.

The operation of the device will be readily understood by reference to the drawings. Fig. 1 shows the coupling member 2 in its operative position, in which it is of course in longitudinal alinement with the shaft 1. It is shown as about to be engaged with the hollow end of a music-roll 3. The music-roll here shown has a hollow end, in this case formed by a sleeve 31. The portion 26 of the flange 25 enters this hollow end of the roll 3 and serves to center and support it. The roll 3, as shown, has a bead 32 on the sleeve 31, in which is cut a notch or recess 33, in which notch the pin or tooth 28 engages. The roll 3 is also centered and supported by the engagement of the bead 32 within the outer rim 29 of the flange 25 of the coupling. It is evident that either the engaging portion 26, entering the hollow end of the roll, or the rim portion 29, embracing the bead 32, would alone suffice to hold the roll in position.

Fig. 3 shows the coupling member 2 as being engaged with a winged pin 41 of a music-roll 4, the pin entering the bore 23 and slots 24 of the coupling member, these together forming a clutch.

In Fig. 5 of the drawings the coupling member 2 is shown as turned to its non-operative position, leaving the clutch member 11 at the

end of the shaft 1 ready for engagement with a pin 41 of a roll 4, or rather of a roll of similar pattern but of greater length.

The modified form of my device shown in Figs. 6, 7, and 8 of the drawings is similar in operation and function to that already described. The shaft 101 has a coupling member 111, formed, as before, with a bore 112 and slots 113, adapted to engage with a winged pin, as 41, Fig. 3. In this case, however, the coupling member 111 has two oppositely-disposed bifurcate lugs 114, each carrying a pintle 115 and forming a hinge member for a part of a coupling member 102. Obviously these hinges may be provided with a suitable holding or friction device—*e. g.*, such as is shown in Fig. 4. One part of the coupling member 102 is provided, as before, with an approximately cylindric portion 122, having a bore 123 and slots 124 in its wall. Both parts of the member 102 have flanges 125, formed with centering portions 126, arc-shaped recesses 127, and rim portions 129. In the recess 127 in one of the parts is a pin or tooth 128. It is obvious that when the coupling member 102 is in longitudinal alignment with the shaft 101, as shown in Fig. 6, it is adapted to engage either roll 3 or 4, as above described, and that when the parts of the member are turned back to the position shown in Fig. 8 the coupling member 111 is, as before, ready for engagement with a pin 41. By making the coupling member 102 in two parts, which fold back on opposite sides of the shaft, and especially by making them of unequal segments, as shown, the tendency to "throw" the shaft is obviated or lessened, while at the same time a larger portion of the circumference of the hollow end 31 of the roll or of the periphery of the bead 32 on the roll is engaged.

It is clear that modifications other than those shown may be made in the form of the device without departing from my invention.

In copending applications filed October 13, 1905, Serial Nos. 282,660 and 282,661, respectively, I have shown a hollow-end music-roll provided with a sleeve having an outward beaded in which is cut a notch or recess and a coupling device having a centering or engaging member and a flange provided with a tooth for engaging in such notch and have claimed the same generically. It is obvious that I do not herein claim anything claimed in either of those applications.

What I claim is—

1. In a music-roll-coupling device, a shaft, a coupling member on said shaft for supporting a music-roll, a second coupling member adjustably mounted on said shaft and in its operative position longitudinally alined therewith, and means on said second coupling member for supporting a music-roll.

2. In a music-roll-coupling device, a shaft having at its free end a coupling member for

supporting a music-roll, and a second coupling member movably connected with said shaft and in its operative position longitudinally alined therewith and having at its free end a like member for supporting a music-roll, the end of one of said coupling members being also provided with a second member for supporting a music-roll having a coöperating engaging member differing from that engageable by said first-named members. 75

3. In a music-roll-coupling device, a shaft having at its free end a coupling member provided with a clutch member for engaging and rotating a music-roll, and a second coupling member movably connected with said shaft 80 and in its operative position longitudinally alined therewith and having at its free end a like clutch member for engaging and rotating a music-roll, the end of one of said coupling members being also provided with a second 85 clutch member for engaging and rotating a music-roll having a coöperating clutch member differing from that engageable by said first-named clutch members.

4. In a music-roll-coupling device, a shaft 90 having at its free end a coupling member for supporting a music-roll, and a second coupling member movably connected with said shaft and in its operative position longitudinally alined therewith and having at its free 95 end a plurality of dissimilar members each adapted to engage and support a music-roll.

5. In a music-roll-coupling device, a shaft having at its free end a coupling member for engaging and rotating a music-roll, and a second coupling member movably connected with said shaft and in its operative position longitudinally alined therewith and having at its free end a plurality of dissimilar clutch members each adapted to engage and rotate 105 a music-roll.

6. In a music-roll-coupling device, a shaft having at its free end a coupling member for engaging a non-circular pin on a music-roll, and a second coupling member movably connected with said shaft and in its operative position longitudinally alined therewith and having at its free end a clutch member for engaging a non-circular pin on a music-roll and a second clutch member for engaging and 115 rotating a music-roll having a hollow end. 110

7. In a music-roll-coupling device, a shaft having at its free end a coupling member for engaging a non-circular pin on a music-roll, and a second coupling member movably connected with said shaft and in its operative position longitudinally alined therewith and having at its free end a clutch member for engaging a non-circular pin on a music-roll and also having on its free end means for centering and supporting a hollow-ended music-roll and for engaging a coöperating clutch member at the end of such last-named roll. 120

8. In a music-roll-coupling device, a shaft, a coupling member on said shaft for support- 125

130

ing a music-roll, and a second coupling member pivotally connected with said shaft and adjustable from a longitudinally-aligned operative position to a lateral eccentric non-operative position thereon.

9. In a music-roll-coupling device, a shaft having at its free end a coupling member for engaging a music-roll and provided with a laterally-projecting lug, and a second coupling member having a laterally-projecting lug pivoted to the lug on said first-named coupling member and having at its free end a clutch member for engaging a music-roll.

10. In a music-roll-coupling device, a shaft having at its free end a coupling member for engaging a music-roll and provided with a laterally-projecting lug, and a second coupling member having a laterally-projecting lug pivoted to the lug on said first-named coupling member and having at its free end independent clutch members for engaging different music-rolls.

11. In a music-roll-coupling device, a shaft provided with a clutch or roll-engaging member, and another clutch or roll-engaging member movably connected to the said shaft for movement to and from its operative position.

12. In a music-roll-coupling device, a shaft provided with a clutch or roll-engaging member, and another clutch or roll-engaging member pivotally connected to the said shaft for movement into and out of operative position in alinement with the said shaft.

13. In a music-roll-coupling device, a shaft provided with a clutch or roll-engaging member, and another clutch or roll-engaging member movably connected to the said shaft for movement to and from its operative position, and means for holding the last said member in its inoperative position.

14. In a music-roll-coupling device, a shaft provided with a clutch or roll-engaging member, and another clutch or roll-engaging member movably connected to the said shaft for movement to and from its operative position, and friction-producing means for holding the last said member in its inoperative position.

In testimony whereof I have signed this specification in the presence of two subscribing witnesses.

EDWIN S. VOTEY.
